US00D543006S

(12) United States Design Patent (10) Patent No.: US D543,006 S
Cocco et al. (45) Date of Patent: * May 22, 2007

(54) FILLED SNACK

(75) Inventors: Antonio Cocco, Cisterna di Latina (IT);
Robert Maria Eurlings, Maastricht (NL); Lucas Paulus Hecker, Maastricht (NL); Sandro Panaïoli, Cisterna di Latina (IT)

(73) Assignee: Unilever Bestfoods, North America, division of Conopco, Inc., Englewood Cliffs, NJ (US)

() Term: 14 Years

(21) Appl. No.: 29/209,650

(22) Filed: Jul. 20, 2004

(30) Foreign Application Priority Data

Jan. 23, 2004 (GB) 3015903

(51) LOC (8) Cl. 01-01

(52) U.S. Cl. D1/199

(58) Field of Classification Search D1/100-30,
D1/199; 426/94, 128, 138, 293, 446, 496,
426/502-4, 549, 556, 805, 808

See application file for complete search history.
